(57) **CLAIM**

The ornamental design for a vehicle headlamp, as shown and described.

DESCRIPTION

FIG. 1 is a front and left side perspective view of a vehicle headlamp showing our new design;

FIG. 2 is a front elevation view thereof;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle headlamp that form no part of the claimed design. The mirror image of the vehicle headlamp of FIG. 1 is claimed, but not shown.
